[57] CLAIM

The ornamental design for a barstool, as shown and described.

DESCRIPTION

FIG. 1 is a perspective view of a barstool showing my new design;

FIG. 2 is a rear elevational view;

FIG. 3 is a side elevational view, the opposite side being a mirror image thereof;

FIG. 4 is a top plan view; and

FIG. 5 is a perspective view of an alternate embodiment, showing my new design.

FIG. 3

FIG. 5
